Term of patent 3½ years

(Cl. D51—1)

Fig. 1

Fig. 3

Fig. 4

Fig. 2

Figure 1 is a front perspective view of a sidewalk subgrader embodying my new design;

Figure 2 is a rear elevational view thereof, on an enlarged scale, a portion of the handle being broken off for convenience of illustration;

Figure 3 is a fragmentary rear elevational view of the right side thereof on an enlarged scale; and

Figure 4 is a left side elevational view thereof on an enlarged scale, a portion of the handle being broken off for convenience of illustration.

The characteristic features of my design for a sidewalk subgrader reside in the grader blade as shown.

I claim:

The ornamental design for a sidewalk subgrader, as shown and described.
